UNITED STATES PATENT OFFICE

FRIEDRICH DUWE, OF MAINZ, GERMANY, ASSIGNOR TO MASCHINENFABRIK AUGSBURG-NÜRNBERG A. G., OF NUREMBERG, GERMANY, A CORPORATION OF GERMANY

SLUICE-GATE FOR WEIRS

Application filed June 3, 1929, Serial No. 363,031, and in Germany June 6, 1928.

My invention relates to weirs and more particularly to weirs equipped with a sluice-gate adapted to be raised and lowered by means of racks and provided with an ice-guard adapted to be raised and lowered prior to the lifting of the sluice-gate. As in common the racks are connected with the ice-guard by means of a lever mechanism permitting the racks during adjustment of said ice-guard to freely move along the body of the sluice-gate so that the sluice-gate will be lifted by the racks only after a catch provided at the lower end of the racks engages fixed stops on the sluice-gate.

15 The present invention now has for its object a novel construction of sluice-gates permitting them to be raised and lowered prior to the raising and lowering of the ice-guard and to be held in a more or less inclined intermediate position.

20 This object I attain by providing in addition to said catch locking bolts made displaceable by means of push-rods movable along said racks to lock the latter with the sluice-gate in any desired position of the ice-guard.

25 In the accompanying drawings in which I have shown various embodiments involving the invention, Fig. 1 is a side-view of an assembled roller sluice-gate provided with locking means for the racks; Figs. 2 and 3 are detail views showing on a somewhat larger scale the locking bolts in a position to lock the racks when the ice-guard is raised; Fig. 4 is a detail view showing on a still larger scale the arrangement of the locking bolts; Figs. 5 and 6 are further detail views showing hook-shaped bolts for keeping the racks in fixed position when the ice-guard is lowered; Fig. 7 is a side-view of a sluice-gate comprising

30 several superposed locking bolts for the purpose of securing the racks in various intermediate positions of the ice-guard; Figs. 8 and 9 are views of a further modification in which the racks may be secured in various positions 35 of the ice-guard by means of locking bolts in the shape of supporting levers mounted on the sluice-gate and adapted to co-operate with the teeth of the racks.

According to Figs. 1-4 the pivoted ice-guard 1 may be erected in the lowered posi-

tion of the sluice-gate 2 by a further lowering of the racks 3 provided on either side of said sluice-gate, and connected for this purpose with said ice-guard 1 by means of levers 4 and links 5 the latter being mounted on the 55 sluice-gate 2. These links 5 on the one hand engage with the levers 4 and on the other hand with cranks 6 mounted on the shaft of the ice-guard, said shaft being constructed to resist torsional strains. At the under 60 ends of the racks 3 there are provided catches 7 which during the raising of the racks 3 and after the lowering of the ice-guard 1 abuts against fixed stops 8 on the sluice-gate 2 causing the latter to positively move in upward 65 direction during the further raising of the racks 3.

In order to permit the sluice-gate 2 to be raised when the ice-guard 1 is raised, the racks 3 are equipped on the side with tracks, 70 in which locking bolts 9 are displaceably arranged underneath the stops 8 on the sluice-gate. Fig. 4 shows more particularly how these locking bolts 9 may be properly set by means of a two-arm lever 10 carried by a 75 shaft 11 which is mounted in the said tracks by means of members 12 provided intermediate said tracks. A forked lever 14 is pivoted to a crank 13 secured to said shaft 11, the other end of said lever, as shown for instance in Fig. 3, being pivoted to a system of 80 levers 15, 16 mounted upon one of the tracks of the rack 3 and extending around the other rack. Another rack 17 pivoted to said lever system 15, 16, is guided by rack 3 to permit 85 relative movement in vertical direction. The rack 17, as Fig. 1 shows, meshes with a pinion 18 which is equipped with a crank-handle 19 mounted upon the upper end of the rack 3.

If it is desired to raise the sluice-gate in the raised position of the ice-guard 1, the racks 17 which are guided by the racks 3 are lowered by means of the crank-handle 19 in the lowered position of said racks 3. Thereby the locking bolts 9 by means of the levers 90 and links 10-16 are moved so as to project into the path of the fixed stops 8 on the sluice-gate 2 and the latter together with the raised ice-guard 1 may now be raised by the racks 3.

In the modification shown in Figs. 5 and 6,

the racks 3 are connected with the ice-guard 1 by means of a link 20 pivoted to a crank on the shaft carrying said ice-guard so that the latter may be lowered in the lowered position of said racks. Instead of the plain locking bolts shown in Figs. 1-4 hook-shaped locking bolts 21 are used in the shape of two-arm levers having arms of even length and loosely mounted upon a shaft 22 carried by the tracks of the rack 3. The downwardly directed arms of these levers 21 are obliquely recessed so as to form in position of rest an acute angle 23, (Fig. 5); while the upper arms have a gap 24 therebetween. A wedge 25 with its edge downwardly directed projects into said gap 24, said wedge being secured by means of bolts 32 on a slide-rod 31 guided on the outside of one of the tracks of the racks 3 and guided also on another rack 30 on the other track. The bolt 32 more particularly is guided in tracks 33 provided on the rack 3. To the free end of the rack 30 which is guided by the rack 3 and to the free end of the slide-rod 31 extending in the position of rest of the hook-shaped levers 21, a little below said hooks there is secured a second wedge 34 by means of bolts 35 which are guided by tracks 36 on the rack 3. The edge of the wedge 34 projects upwards into the angle 23 formed by the obliquely recessed levers 21.

In this arrangement, the levers 21 remain at rest when the sluice-gate 2 is raised in the erected position of the ice-guard. The said levers, however, will disappear intermediate the tracks on the racks 3 so that the latter may be raised when the ice-guard 1 is erected until the catches 7 abut against the fixed stops 8 on the sluice-gate.

If, however, during the raising of the sluice-gate the ice-guard 1 shall remain in the lowered position, the pull exerted upon the rack 30 will cause the wedge 34 at the under end of said rack to move in upward direction, in which case the oblique surfaces of said wedge 34 will exert a pressure upon the oblique surfaces of the levers 21 so that the latter will be spread apart, thus bringing them into the path of the stops 8 provided on the sluice-gate 2. During the raising of the racks 3, therefore, the sluice-gate will at once be positively raised together with said racks. After the lowering of the sluice-gate, the levers 21 are returned to their initial position by a downward motion of the racks 30, the upper wedge 25 in this case being introduced into the gap 24 intermediate said levers 21 after the lower wedge 34 has been moved to some extent away from said levers.

By reason of the spreading action exerted by the wedge 25, the hooks 21 will be rocked inwardly so that the sluice-gate will be disengaged therefrom.

The modification shown in Fig. 7 will not only permit the raising of the sluice-gate in

the erected and lowered position of the ice-guard 1 but also in three intermediate positions thereof. For this purpose four spaced locking bolts 37-40 of like construction such as shown in Figs. 1-4, are provided in addition to the fixed catch 7, on the racks 3. These locking bolts 37-40 are actuated by means of a common rack 41 guided intermediate the tracks on the racks 3 as well as by means of a link 42 which engages directly with the cranks of the operating members for said locking bolts. The ice-guard 1 in the present case is connected with the rack 3 by means of a link 43 engaging therewith, a bell-crank 44 pivotally connected with said link 43 and mounted on the sluice-gate 2 and a further link 45 leading from said bell-crank 44 to the crank 6 of the shaft for operating the ice-guard 1, in a manner to permit the same to be raised while the rack 3 is in its lowermost position.

If it is desired to lower the ice-guard 1 before the sluice-gate 2 is raised, the levers 37-40 are left at rest so that during the raising of the rack 3 the catch 7 will cause upward motion of the sluice-gate 2 by means of the stops 8 after the lowering of the ice-guard 1.

On the other hand, if it is desired to retain the ice-guard prior to the raising of the sluice-gate in partly raised position, as for instance in a position which corresponds to about one fourth of the total rocking motion of the ice-guard, the racks 3 are only lifted to such an extent that the lowermost locking bolt 37 comes into position underneath the stops 8 on the sluice-gate. The ice-guard then will be lowered through an angle corresponding to about three quarters of its rocking motion. Now, when the rack 41 is moved the bolts 37-40 will be moved forward so that the lowermost bolt 37 will engage the stops 8, while the locking bolts 38-40 will be positioned within recesses 46-48 provided in the sluice-gate. The sluice-gate may now be lifted upon a further raising of the rack 3.

In like manner, the racks 3 are lifted to a proper extent before the bolts 37-40 are unlocked, if the ice-guard 1 shall remain in half-raised or in about three quarter raised position. In such case the bolts 38 and 39 will be moved into the range of action of the stops 8, thus causing either the bolts 39 and 40 or only the bolt 40 to engage with the recesses 46, 47 or 48, respectively. By immediately unlocking the bolts before the raising of the rack 3, the sluice-gate may also be raised when the ice-guard 1 is in fully raised position.

According to Figs. 8 and 9 the locking between the sluice-gate and the racks 3 is accomplished by means of locking bolts 49 having the form of supporting levers pivotally mounted by means of the shaft 50 on the side of the sluice-gate to co-operate with the teeth 51 of the racks 3. By this construction of the locking bolts it will be possible to adjust, prior to the lifting of the sluice-gate,

the ice-guard 1 in the same manner as shown in Fig. 5 by means of a link 20 pivoted to the crank 6 mounted on the shaft of the ice-guard in various angular positions determined by the distances intermediate the teeth 51 on said rack. For this purpose a fork-shaped crank 52 is secured on shaft 50, and united into a lever-parallelogram with the lever 55 which is pivoted to the link 53 by means of a lever 55 mounted on a fixed supporting wall 54 of the sluice-gate. The link 53 carries a fixed bolt 56 which is guided within a relatively long slot 57 provided in the connecting rod 58. This connecting rod 58 is pivoted at its two ends to the levers 59 and 60, respectively, which levers are mounted on shafts 61 and 62 in the tracks of the racks 3.

The length of the slot 57 is so dimensioned that during the raising and lowering of the ice-guard 1 the connecting rod 58 may slide upon the bolt 56. Mounted upon the shafts 61 and 62 are other levers 63 and 64 which are in engagement with the rod mechanism 25 for operating the locking device, which mechanism consists of the rack 65 and the connecting rod 66.

When the sluice-gate 2 is raised with the ice-guard 1 in raised position, the supporting lever 49 will remain at rest. If it is desired, however, to lower the ice-guard 1 prior to the raising of the sluice-gate, the rod mechanism 65 and 66 is actuated in the lowered position of the rack 3. Consequently of this, the levers 63 and 64 as well as 59 and 60 will rock outwards and cause a displacement of the connecting rod 58 so that the latter will move from the right-hand position shown in Fig. 8 toward the left so that the parallelogram of levers 53, 55 and 52 which is positively moved by means of the bolt 56 will rock the supporting lever 49 into the broken-line position in which it will engage with the uppermost tooth 51 of the rack 3 which tooth is positioned in the path of said supporting lever 59. If now the racks 3 are raised, the sluice-gate likewise will be raised together with the ice-guard in lowered position.

In order to retain the ice-guard 1 in an intermediate position, the racks 3 before actuation of the rod mechanism 65 and 66 need to be raised only to such an extent that a definite tooth 51 of the rack will engage with the supporting lever 49 subsequent to the outward rocking motion of the latter.

The last-described arrangement has special advantages, inasmuch as only one rod mechanism 65, 66 will be required for the operation of the supporting levers which co-operate with both racks of the sluice-gate. This is due to the fact that the shaft 50 which carries the supporting levers or bolts 49 may be made to extend all over the width of the sluice-gate, thus permitting

positive motion to be transmitted from one to the other side of the sluice-gate.

The invention may of course, be embodied in other modifications different from those shown and described herein and, therefore, I do not limit myself to the disclosure made in this specification and the drawings.

I claim:

1. In a weir, a vertically movable sluice gate, an ice-guard mounted on said sluice gate for movement to raised and lowered positions relative thereto, vertically movable racks for raising and lowering the sluice gate, said racks being vertically movable relative to the sluice gate, connections between said racks and said ice-guard whereby vertical movement of the racks relative to the sluice gate effects raising and lowering of the ice-guard, stops carried by the sluice gate, locking bolts carried by the racks for projection to engage said stops upon upward movement of the racks to cause the sluice gate to be lifted with the racks, and means mounted on the racks for effecting projection and retraction of said locking bolts.

2. In a weir, a vertically movable sluice gate, an ice-guard mounted on said sluice gate for movement to raised and lowered positions relative thereto, vertically movable racks for raising and lowering the sluice gate, said racks being vertically movable relative to the sluice gate, connections between said racks and said ice-guard whereby vertical movement of the racks relative to the sluice gate effects raising and lowering of the ice-guard, locking elements carried by the racks and the sluice gate, respectively, for co-operation with each other to lock the sluice gate to the racks for upward movement by the latter, and means carried by the racks for operating the locking elements carried thereby to and from positions for cooperation with the locking elements carried by the sluice gate.

3. In a weir, a vertically movable sluice gate, an ice-guard mounted on said sluice gate for movement to raised and lowered positions relative thereto, vertically movable racks for raising and lowering the sluice gate, said racks being vertically movable relative to the sluice gate, connections between said racks and said ice-guard whereby vertical movement of the racks relative to the sluice gate effects raising and lowering of the ice-guard, locking elements carried by the racks and the sluice gate, respectively, for cooperation with each other to lock the sluice gate to the racks for upward movement by the latter in different vertical positions of the racks relative to the sluice gate, whereby the sluice gate may be raised with the ice-guard disposed in different positions of adjustment relative thereto, and means carried by the racks for effecting relative op-

110
115
120

eration of the locking elements to and from cooperating positions.

4. In a weir, a vertically movable sluice gate, an ice-guard mounted on said sluice gate for movement to raised and lowered positions relative thereto, vertically movable racks for raising and lowering the sluice gate, said racks being vertically movable relative to the sluice gate, connections between said racks and said ice-guard whereby vertical movement of the racks relative to the sluice gate effects raising and lowering of the ice-guard, a plurality of vertically spaced locking elements carried by the racks, co-operating locking elements carried by the sluice gate to lock the sluice gate to the racks for upward movement by the latter in different vertical positions of the racks relative to the sluice gate, whereby the sluice gate may be raised with the ice-guard disposed in different positions of adjustment relative thereto, and means carried by the racks for effecting relative operation of the locking elements to and from cooperating positions.

5. In a weir, a vertically movable sluice gate, an ice-guard mounted on said sluice gate for movement to raised and lowered positions relative thereto, vertically movable racks for raising and lowering the sluice gate, said racks being vertically movable relative to the sluice gate, connections between said racks and said ice-guard whereby vertical movement of the racks relative to the sluice gate effects raising and lowering of the ice-guard, locking elements carried by the racks and the sluice gate, respectively, for cooperation with each other to lock the sluice gate to the racks for upward movement by the latter, and means carried by the racks for effecting relative operation of said locking elements to and from cooperating positions.

In testimony whereof I affix my signature.
FRIEDRICH DUWE.
